(57) **CLAIM**

The ornamental design for a pen stand, as shown and described.

DESCRIPTION

FIG. 1 is a top front right perspective view of a pen stand showing my new design;

FIG. 2 is a bottom front left perspective view of FIG. 1;

FIG. 3 is a front elevation view of FIG. 1;

FIG. 4 is a rear elevation view of FIG. 1;

FIG. 5 is a left side elevation view of FIG. 1;

FIG. 6 is a top plan view of FIG. 1;

FIG. 7 is a bottom plan view of FIG. 1;

FIG. 8 is a top front right perspective view of a first portion of FIG. 1, shown without a second portion for convenience;

FIG. 9 is a bottom front left perspective view FIG. 8;

FIG. 10 is a front elevation view of FIG. 8;

FIG. 11 is a rear elevation view of FIG. 8;

FIG. 12 is a left side elevation view of FIG. 8, wherein the right side elevation view is a mirror image of the left side elevation view;

FIG. 13 is a top plan view of FIG. 8;

FIG. 14 is a bottom plan view FIG. 8;

FIG. 15 is a top front right perspective view of the second portion of FIG. 1, shown without the first portion for convenience;

FIG. 16 is a front elevation view of FIG. 15;

FIG. 17 is a rear elevation view of FIG. 15;

FIG. 18 is a left side elevation view of FIG. 15;

FIG. 19 is a right side elevation view of FIG. 15;

FIG. 20 is a top plan view of FIG. 15;

FIG. 21 is a bottom plan view of FIG. 15; and,

FIG. 22 is a bottom front left perspective view of FIG. 1, with the second portion removed and a plurality of pen nibs disposed therein.

The evenly spaced broken lines in FIGS. 1-22 show nibs and portions of the pen stand that form no part of the claimed design. The long and short broken lines in FIGS. 9, 14 and 22 define the bounds of the claimed design and form no part thereof.
